(57) **CLAIM**

The ornamental design for a pump with pressure gauge, as shown and described.

DESCRIPTION

FIG. 1 is a front view of a pump with right/angular handle, including valve connector;

FIG. 2 is a front view of a pump with angular handle, including valve connector;

FIG. 3 is a top view of a pump with angular handle in position 2, including valve connector;

FIG. 4 is a top view of a pump with angular handle in position 2, including valve connector;

FIG. 5 is front view of a pump with angular handle in position 2, including valve connector;

FIG. 6 is a front view of a pump with angular handle in position 2, with pressure gauge, including valve connector;

FIG. 7 is a top view of a pump with angular handle in position 1, with pressure gauge, including valve connector;

FIG. 8 is a front, top detail view of an angular handle in position 1, hose suspension and pressure gauge;

FIG. 9 is a front side view of a foot of pump, including connector;

FIG. 10 is a front side view of the underside of the foot of a pump, including connector; and,

FIG. 11 is a top view of a pressure gauge, valve connector.
